UNITED STATES PATENT OFFICE.

THOMAS H. SEELY, OF BOSTON, MASSACHUSETTS, ASSIGNOR TO UNITED SHOE MACHINERY COMPANY, OF PATERSON, NEW JERSEY, A CORPORATION OF NEW JERSEY.

PACKAGE OF WELTING.

1,101,212.

Specification of Letters Patent. Patented June 23, 1914.

Application filed February 24, 1913. Serial No. 750,308.

To all whom it may concern:

Be it known that I, THOMAS H. SEELY, a citizen of the United States, residing at Dorchester, Boston, in the county of Suffolk and 5 State of Massachusetts, have invented certain new and useful Improvements in Packages of Welting; and I do hereby declare the following to be a full, clear, and exact description of the invention, such as will enable others skilled in the art to which it 10 pertains to make and use the same.

The present invention relates to a package of welting, and more particularly to a package of welting which can be readily 15 permeated by water to temper the welting.

The welting is usually supplied to the shoe manufacturer in compact tightly-coiled rolls. In order to prepare the welting for sewing it to the lasted shoe, it is usually run 20 through a grooving and beveling machine which cuts a stitch-receiving groove in the face of the welt and bevels the edge of the welt. It is desirable, particularly where any 25 quantity of prepared welting is kept in stock, that the prepared welting be kept in compact packages which are convenient to handle. After the prepared welting is delivered to the operator of the welt sewing machine, and before it is sewn to the shoe, 30 the welting is soaked in water to soften or temper the leather so that the welt is more easily applied and sewn to the shoe. In order that the welting may be conveniently 35 tempered by the operator before he uses it on the welt sewing machine, the package in which the welt is supplied to him should be capable of being readily permeated by water to temper the welting.

The object of the present invention is to 40 provide a package of welting which can be conveniently handled and which can be readily permeated by water to temper the welting preparatory to sewing it to the shoe.

With the above object in view, the present 45 invention consists of the package of welting hereinafter described and particularly pointed out in the claims.

In the drawings which illustrate the preferred embodiment of the present invention, 50 Figure 1 is a perspective view of the package of welting; and Fig. 2 is a side elevation.

Referring to the drawings, the package 55 of welting is a coil of a generally cylindrical outline and of a greater length, taken along

its axis, than the width of the welt strip. The package or coil consists of a continuous strip 1 of welting coiled in a flat or untwisted condition and deflected back and forth longitudinally of the coil to form criss-crossed or intersecting spirals. The length of the welt strip is such that the coil is made up of a number of layers or thicknesses of welt, the number of layers, of course, depending upon the length of the welt strip. In the coil 39 illustrated in the drawings, each spiral extends five-eighths of the distance around the circumference of the coil. In making this coil, after one spiral has been wound, the welt is deflected toward the opposite end 65 of the coil and is wound five-eighths of the distance around the circumference of the coil to form a second spiral. These two spirals taken together extend one and one-quarter turns around the coil so that the 70 third spiral begins one-quarter of the circumference of the coil in advance of the beginning of the first spiral. The winding is continued and the welt is deflected back and forth until eight spirals have been wound, the welting in these eight spirals forming 75 five complete turns around the coil. The ninth spiral will be wound directly over the first spiral, the tenth spiral will be wound directly over the second spiral, and so on. 80 The coil illustrated in the drawings will therefore consist of eight sets of spirals, each set of which consists of the superposed parallel spiral layers or laminæ of welting which are laid flat one on top of the other 85 in the process of winding. Four of these eight sets extend in the same direction longitudinally of the coil and are spaced apart 90 from each other one-quarter of the distance around the coil. The other four sets extend in the opposite direction longitudinally of the coil, are spaced apart from each other one-quarter of the circumference of the coil and intersect or criss-cross the first four sets. 95 In the side elevation of the coil, shown in Fig. 2, the outside spirals of five of these eight sets are visible. The outside spirals 5, 7 and 9 form the top layers of three of the sets which extend in the same direction, the fourth set being at the back side of the coil and therefore not visible. The spirals 6 and 8 are the top layers of two of the other four sets, the other two sets of this four being on 100 the back side of the coil and therefore not visible. These five outside spirals 5, 6, 7, 8 105 110

and 9 intersect or criss-cross each other at the points 10, 11, 12, 13 and 14. Beneath these outside spirals are the inner spirals forming the inner layers or laminæ of the 5 sets.

As shown in Fig. 2, the set of which 7 is the outer spiral consists of a plurality of inner spiral layers or laminæ 20, 21, 22, and so on radially into the coil. The spirals 10 which extend in the same direction and which are adjacent are, as above pointed out, spaced apart a quarter of the circumference of the coil so that spaces or interstices are left between the edges of the welt. As 15 shown in Fig. 2, the space between the edges of two adjacent spirals is greater than the width of the welt strip. Since the welting is coiled in a plurality of sets of superposed layers or laminæ, the spaces or interstices 20 between the edges of the spirals which form these layers or laminæ coincide to form holes, such as 25 and 26, which extend substantially radially into the coil between said layered sets of spirals. At the points of 25 intersection of the spirals, the layers or laminæ of each set are alternately interposed so that between such points of intersection, the layers or laminæ are separated from each other to leave spaces or interstices 30 between the opposing flat faces of the welting of the superposed layers. Such interstices are shown, for example, at 30 and 31 in Fig. 1 and at 32 and 33 in Fig. 2 of the drawings. The interstices between the welt 35 layers, such as 7, 20, 21 and 22 separate these layers between points of intersection 11 and 12 and form connecting interstices between the holes 25 and 26. Between the points of intersection, the welting is, therefore, exposed on all sides, so that it can readily absorb moisture. The entire package or 40 coil is honey-combed with spaces or interstices between the edges and the faces of the welting and when this open-work package 45 or coil is dropped into water it is readily permeated by it. The package is tied together by two strings 35 and 36 which prevent the welting from uncoiling and keep it in convenient condition for handling.

50 The welt strip is sufficiently broad so that it cannot be easily bent laterally. If it is attempted to bend the welt strip sharply laterally, the stiffness of the strip will resist such lateral bending. Moreover, if the welt 55 is given a comparatively sharp lateral bend it will cause one edge to be curled or buckled. The welt strip, however, can be readily bent in the direction of its thickness. Consequently, as is clearly shown in the 60 drawings, the welt strip at the ends of the coil where the strip is deflected is not bent sharply laterally of the strip but lies in a surface which is inclined to the axis of the coil. This surface is a ruled surface, the 65 generating line of which moves about and is

inclined to the axis of the coil and the surface is inclined in such a direction that it intersects the axis of the coil beyond the end of the coil. By virtue of the slight twisting of the welt strip so that its edge 70 nearest the end of the coil is nearer the axis of the coil than the other edge of the strip, the surface in which the welt strip lies is changed from the cylindrical surface in which it lies at the middle of the coil into a surface which is inclined to the axis of the coil, and which is in conformation something like a part of a cone. The effect of so inclining the welt strip at the end of the strip, is to cause its deflection longitudinally by bending it in the direction of its thickness instead of in the direction of its width.

The package or coil of welting of the present invention is compact enough so that 85 it is easily handled and stored, but at the same time it can be readily permeated by water to temper the welting. The operator of the welt sewing machine can drop the package as it is delivered to him, directly 90 into the water to temper the leather. The package of soaked or tempered welting is in a convenient form to handle and use on the welt sewing machine when it is taken out of the water. The open-work package or 95 coil is so readily permeable by water that the operator of the welt sewing machine need not unwind the welt, but simply has to drop the open-work package or coil into the water and let it stay there until he needs 100 more welting for his machine.

While the preferred embodiment of the present invention has been specifically illustrated and described, the present invention is not limited to its preferred embodiment, 105 but may be embodied in other packages or coils of welting within the scope of the invention as set forth in the following claims:

1. As an article of manufacture, a package or coil of welting of a generally cylindrical outline and of greater length than the width of the welt strip, consisting of a continuous strip of welting in a flat or un-twisted condition arranged in criss-crossed or intersecting spirals extending back and forth longitudinally of the coil and separated from each other to form an open-work package or coil of welting which can be readily permeated by water to temper the 115 welting preparatory to sewing it to a shoe.

2. As an article of manufacture, a package or coil of welting of a generally cylindrical outline and of greater length than the width of the welt strip, consisting of a continuous strip of welting in a flat or un-twisted condition arranged in criss-crossed or intersecting spirals extending back and forth longitudinally of the coil, said spirals 125 being arranged in a plurality of sets of su- 130

- perposed parallel spiral layers or laminæ of 5
welting laid flat one on top of the other and
spaced apart to leave holes extending sub-
stantially radially into the coil between said
sets, the layers or laminæ of two such sets
being alternately interposed at the points of
intersection of the spirals and the layers or
laminæ of each set being separated from
each other between such points of intersec-
tion to leave the welt strip exposed on all
sides, so that the package or coil of welting
can be readily permeated by water to tem-
per the welting preparatory to sewing it to
a shoe.
- 15 3. As an article of manufacture, a pack-
age or coil of welting of a generally cylin-
drical outline and of greater length than
the width of the welt strip, consisting of a
continuous strip of welting in a flat or
20 untwisted condition arranged in criss-
crossed or intersecting spirals extending
back and forth longitudinally of the coil,
each spiral being separated from the other
spirals except at points of criss-crossing or
25 intersection to leave interstices between the
opposing edges and the opposing faces of
the spirals through which water can perme-
ate the entire package or coil to temper the
welting preparatory to sewing it to a shoe.
- 30 4. As an article of manufacture, a pack-
- age or coil of welting of greater length than
the width of the welt strip, consisting of a
strip of welting deflecting back and forth
longitudinally of the coil to form criss-
crossed or intersecting spirals separated 35
from each other to form an open-work pack-
age of welting which can be readily perme-
ated by water to temper the welt prepara-
tory to sewing it to a shoe, said welt strip
at the points of deflection lying in surfaces 40
which are inclined to the axis of the coil.
5. As an article of manufacture, a pack-
age or coil of welting of greater length than
the width of the welt strip consisting of a
strip of welting in a flat or untwisted con- 45
dition deflected back and forth longitudi-
nally from end to end of the coil in criss-
crossed or intersecting spirals separated
from each other to form an open-work pack-
age or coil of welting which can be readily 50
permeated by water to temper the welting
preparatory to sewing it on a shoe, said
welt strip at the points of deflection having
its edge nearest the end of the coil nearer
the axis of the coil than its other edge.
